ATTORNEY

UNITED STATES PATENT OFFICE.

JAMES E. BRIGGS, OF WATERLOO, IOWA.

DUMPING-WAGON.

No. 926,724

Specification of Letters Patent. Patented July 6, 1909.

Application filed August 14, 1908. Serial No. 448,496.

To all whom it may concern:

Be it known that I, JAMES E. BRIGGS, a citizen of the United States of America, and a resident of Waterloo, Blackhawk county, Iowa, have invented certain new and useful Improvements in Dumping - Wagons, of which the following is a specification:

My invention relates to improvements in dumping wagons, and the object of my improvement is to provide an efficient bottom-dumping wagon, and one whose rear door is adapted for vertical displacement and adjustment when dropped, to permit it to pass without touching the materials deposited from such wagon. This object I have accomplished by the means which are herein-after fully described and claimed, and which are illustrated in the accompanying drawings, in which:

Figure 1 is a left-hand side elevation of my improved dumping-wagon, showing it with its bottom-dumping doors lowered as in operative position to discharge a load. Fig. 2 is a rear elevation of said wagon. Fig. 3 is a perspective detail of the hand-levers and their rock-shafts. Fig. 4 is a detail view of part of the adjusting-means for the rear dumping-door.

Similar numbers refer to similar parts throughout the several views.

The wagon-body 1 is supported on and in a frame composed of bars 2, the latter supported on axles 49 and 53 and carrying-wheels 42 and 40. The bottom of the box 1 consists of swinging-doors 10 and 16 coöperating with an intermediate transverse fixed plate 13. The forward door 16 is simply hinged at 33 directly to the lower forward edge of the box 1, but the rear door 10 is differently connected to the rear lower edge of said box. Eyebars 9 are secured to the rear upper edge of the said rear door 10, and links 8 are connected between the eyes of said bars and the forward ends of cranks 3 secured, spaced apart, to the transverse rock-shaft 4 mounted in bearings on the frame 2. The downturned left-hand end of the said rock-shaft forms a crank whose end is pivoted to a connecting-rod 32. The forward end of the rod 32 is pivoted to the lower end of a swing-arm 24, whose upper end is hung in a bearing projected from the upper part of the box 1. A connecting-rod 38 is used to connect the swing-arm 24 and a hand-lever 34, the lower end of the latter being pivoted at 37 to the frame 2, and said lever having a

pivoted pawl 35 adapted to engage the teeth of a rack-bar 36 so as to be secured in an adjusted forward or back position. When the rear door 10 has been lowered by means to be hereinafter described, the hand-lever 34 may be so shifted in position as to, by means of the above described connections, rock the shaft 4, which causes the arms or links 8 to draw up said door 10 to clear any load which may have been deposited in front of it from said box. To keep the door 10 from swinging out of line, I have provided its upper edge with a plurality of rings 44 which pass slidably over the inclined slide-bars 7, the lower ends of the slide-bars being secured to the box 1 at its rear lower edge, and their upper ends to a transverse bar 45 secured to the rear ends of the frame-bars 2.

The numeral 51 designates an adjustable transverse bar having orifices at each end to receive the limbs of U-bolts 50, the latter secured to said bar 51 by nuts 52. The loops of said U-bolts slide upon the slide-bars 7, and the bar 51 may be adjusted to a desired height along the bars 7 by tightening the nuts 52 to secure them together at the proper location. Then the bar 51 becomes a stop for the door 10 to limit the amount of its vertical lift.

The doors 10 and 16 are lowered or elevated by means of the hand-levers 31 and 30. Said hand-levers are fixed respectively to the parallel rock-shafts 48 and 47 whose ends, see Fig. 3, are mounted in the sides of the frame, and project therefrom, being turned up to form the cranks 29 and 28 respectively on each side. Said cranks have respectively eyes 26 and 27, in which are secured the forward ends of chains 14 and 15 respectively, the rear ends of said chains being secured at 18 and at 17 respectively to the doors 10 and 16.

The numerals 19 and 11 designate brackets on the sides of the box 1. The chain 15 on each side is passed over an idler 21 pivoted to the brackets aforesaid at their point of junction, while the chain 14 on each side is passed over idlers 20 and 12 pivoted respectively to the brackets 19 and 11, this means of suspension permitting an upward draft from such chains upon said doors 10 and 16 without binding.

To lower both doors at once to dump the entire load, it is only necessary to throw back the lever 30, when the crank 28 on each side will contact with and force back the cranks 29 thus slackening both of the chains

15 and 14 simultaneously. Both doors are raised by reversing the above action, except that the handle 31 is grasped, the cranks 29 pushing forward the cranks 28. In case it is desired to dump but one half the load, the lever 31 only is thrown back. The load having been dumped, the forward lever 34 may be used to elevate the rear door 10, in order to allow of the box 1 passing over the load in moving forward, without interference of said rear door with the deposited load thereunder. The rear door may then be lowered to the position shown in Fig. 1 by throwing the lever 34 in the reverse direction, and the doors then swung upward by the levers 30 and 31, used conjointly. When the levers 30 and 31 are thrown forward to close the doors the connections at 26 and 27 pass the dead-centers, which holds the doors in place. To adjust the length of the chains 14 and 15 to keep said doors tightly closed to prevent leakage, turn-buckles 54 and 55 are inserted in them as shown in Fig. 1. The transverse partition 23 helps to so divide the load that when the rear door only is opened, only a part of the load is discharged. The rear door 10 when adjusted slidably a desired height, may be drawn with the vehicle forward, the lower edge of door grading to an equal height the load thereunder.

Having described my invention, what I claim as new, and desire to secure by Letters Patent, is:

1. In combination, a transportable receptacle, a slideway on one end thereof, said receptacle having a forwardly swinging drop-door and a rearwardly swinging drop-door, the latter suspended from said slideway and adapted to slide therealong, and means for positively sliding said rear door upward along said slideway when it is swung open.

2. In combination, a transportable receptacle, slideways, on one end thereof, said receptacle having a forwardly swinging drop-door and a rearwardly swinging drop-door, the latter suspended on said slideways and slideable thereover when swung open, a hand-lever, a rock-shaft having crank-arms, linking-connections between said crank-arms and said rear drop-door, a crank-arm on said rock-shaft projected therefrom at an

angle to the other crank arms, and a linking-connection between the hand-lever and said last-mentioned crank-arm.

3. In combination, a transportable receptacle, slideways on one end thereof, said receptacle having a swinging drop-door suspended from and slideable upward over said slideways, means connected to said drop-door adapted to move it positively upward over said slideway when swung open, a yoke whose looped ends encircle said slideways above and in the path of movement of said drop-door, and means for adjustably securing said yoke upon said slideways to adjustably limit the upward movement of said door.

4. In combination, a transportable receptacle, swinging drop-doors therein, two parallel rock-shafts, a hand-lever on each rock-shaft, and a crank-arm on each rock-shaft, said crank-arms adapted to become engaged and be thrown together past their dead centers when one of said hand-levers is thrown in a certain direction, and a linking-connection between each of said crank-arms and one or the other of said swinging-doors respectively, the said doors being held closed when said crank-arms are moved past their dead-centers.

5. In combination, a transportable receptacle, swinging drop-doors therein, two parallel rock-shafts, a hand-lever on each rock-shaft, a crank-arm on each end of each rock-shaft, linking-connections between the crank arms on one rock-shaft and one of said drop-doors, linking-connections between the crank-arms on the other rock-shaft and the other one of said drop-doors, the adjacent crank-arms on each end of said rock-shafts being adapted to become engaged and be thrown together past their dead-centers when one of said hand-levers is shifted in a certain direction to elevate said doors toward said receptacle and hold them closed against it.

Signed at Waterloo, Iowa, this 27th day of July, 1908.

JAMES E. BRIGGS.
